UNITED STATES PATENT OFFICE.

FREDERICK A. STEVENSON, OF DETROIT, MICHIGAN, ASSIGNOR TO AMERICAN CAR AND FOUNDRY COMPANY, OF ST. LOUIS, MISSOURI, A CORPORATION OF NEW JERSEY.

APPARATUS FOR FORMING ANNULAR WORK.

1,224,805.

Specification of Letters Patent.

Patented May 1, 1917.

Application filed December 11, 1915. Serial No. 66,331.

To all whom it may concern:

Be it known that I, FREDERICK A. STEVENSON, residing at Detroit, Michigan, and being a citizen of the United States, have invented

5 certain new and useful Improvements in Apparatus for Forming Annular Work, of which the following is a full, clear, and exact description, such as will enable others skilled in the art to which it appertains to make and 10 to use the same, reference being had to the accompanying drawings, which illustrate the preferred form of the invention, though it is to be understood that the invention is not limited to the exact details of construction shown and described, as it is obvious that various modifications thereof will occur to persons skilled in the art within the scope 15 of the claims.

In said drawings:

20 Fig. 1 is a composite view showing on the left my improved machine in elevation and on the right showing a central vertical section thereof, the parts being in the positions they occupy previous to operating upon 25 work.

Fig. 2 is a plan view of the same, the upper table being omitted.

Fig. 3 is another composite view comprising horizontal sections taken on line 3—3 of 30 Fig. 1, the upper half of said figure being viewed from below and the lower half being viewed from above.

Fig. 4 is a central vertical section corresponding to that shown on the right hand 35 side of Fig. 1 but with the parts in the position they occupy after completing a swaging operation.

Fig. 5 is an enlarged cross section of a ring to be operated upon; and Fig. 6 is another 40 cross section of the same ring after it has been treated by the machine.

The present invention relates to machines for forming rings, one type of ring which it is especially adapted to produce being the 45 firing ring of a shell or projectile.

An object of the invention is to produce a machine adapted to change a ring having the nature of a short cylinder with parallel inner and outer surfaces, to a cylinder of less 50 altitude, having desired configurations on its convex surface. It is also intended that such ring may be so treated by the machine as to produce a portion of increased diameter intermediate the ends of the vertical section 55 of the ring.

A desirable feature is that the ring may be changed from its untreated form to its finished form in a single operation of the machine.

It is, of course, to be understood that the 60 machine may be utilized to produce rings of other cross section than that referred to and configurations in different portions thereof, and other features of merit are present and will be referred to hereinafter, all coming 65 within the scope of the present invention.

Referring to the drawings, 1 indicates an upper table spaced an appropriate distance above the base line of the machine, and 2 a lower table, one table being movable relative 70 to the other. Mounted upon the lower table 2 is a lower die holder 3 which is secured thereto by any suitable means, such as the clamps 4, which are of a well known type and are held in clamping relation by bolts 75 5, which in practice extend into T slots (not shown in table 2). Lower die holder 3 contains a central annular socket in which is mounted an annular lower die 6 which is firmly retained in place by screws 7, the 80 heads of which occupy pockets in the under side of the lower die holder and whose shanks extend upwardly and have their ends threaded into the lower annular die 6.

Spaced and positioned above said lower 85 die is an annular upper die 7 which is seated in an annular socket present in the under side of the upper die holder 8 which has an upwardly extending neck 9, adapted to slide relatively to cylindrical portions of a pilot 90 10 and a pilot holder 11. Upper annular die 7 is provided, on its outer convex surface and intermediate the top and bottom thereof, with an annular and angular groove 24 into which the ends of die-retaining screws 95 25 (shown in Fig. 3) are adapted to be projected and thereby retain the upper die holder in place, the sloping portion of the annular groove serving to give a wedging relation between the end of the screws and the groove face of the upper die. Pilot holder 11 is clamped to the upper stationary table by other clamps and bolts 4 and 5, similar to those holding the lower die in place, and has an internal central hole 105 threaded in its lower portion to receive a threaded stud 12 of the pilot 10. Said pilot also has an internal bore comprising an upper part of smaller diameter and a lower part of greater diameter, the latter terminat- 110

ing at the bottom face of the pilot and containing in its bottom portion recesses 13 which are also open at the bottom face of said pilot and are designed to receive a wrench or other tool, by means of which the pilot stud 12 may be caused to be screwed into the lower portion of the pilot holder 11.

The upper die holder 8 is annular in form, by preference, and at opposite sides 10 has projecting ears 14, through each of which slidably project suspension pins 15 which are provided at their lower ends with heads 16 upon which rest the ears 14 of the upper die holder 8. Near their upper 15 extremities, suspension pins 15 are apertured, preferably by being drilled and countersunk, and through the aperture of each pin 15 extends the hooked end of a suspension spring 17. The upper ends of 20 suspension springs 17 are also formed into hooks which are hung upon the projecting ends of supporting pins 18 and are reliably retained in place by any suitable means, such as the cotter pins 19 which are inserted 25 through the outer ends of said supporting pins 18, outside the upper hook of suspension springs 17. Said upper hooks of springs 17 are prevented from inward displacement by an intermediate shoulder-forming portion 20 of supporting pins 18, 30 said portions 20 also serving to properly position said supporting pins, so that the axes of suspension springs 17 are maintained in predetermined and non-interfering positions 35 with respect to other adjacent movable parts. The inner, and preferably the major, portions of said supporting pins 18, are forced into drilled or other suitably formed holes, in an upper flange 21 of the 40 pilot holder 11, and, therefore, the upper die holder is seen to be resiliently supported from said pins 18.

Annularly arranged on the upper face of upper die holder 8, and on a circle of 45 considerably greater diameter than that of the circumference of upper die holder neck 9, is a series of upwardly extending spring-positioning lugs 22. With their lower ends resting upon the upper face of upper die holder 8, and with their lower portions each surrounding one of these positioning lugs 22, are compression springs 23, the upper ends of which are considerably below the under surface of flange 21 of the pilot holder 11, when the parts of the machine are in the positions they occupy before and between work-treating operations. The function of compression springs 23 will be later referred to.

60 Guide bolts 26 have their lower ends screwed into diametrically opposed feet 27, extending from the major and annular portion of lower die holder 3, the holes into which they are threaded being expanded 65 below a thread-containing portion and the

expanded portions extend to the bottom of the lower die holder whereby vertical adjustment of guide bolts 26 is made possible. After an appropriate vertical adjustment of guide bolts 26 has been made, they 70 are locked in fixed position by nuts 29. The upper portion of shanks of guide bolts 26 extend through holes in the ears 14 of the upper die holder, the latter being slideable vertically relative to the shanks of said 75 guide bolts 26, and the heads 28 of said guide bolts preventing excessive separation of the dies and disconnection between the upper die holder and the guide bolts.

Lower die 6, upper die 7 and pilot 10 80 are provided with work-shaping faces, as follows: Lower die 6 has a lower face 30, slightly inclined upwardly and outwardly and adapted to convert the bottom annular edge 30^a of the ring to be treated, the cross 85 section of which is shown in Fig. 5, to a beveled edge 30^b, shown in the section of the finished ring illustrated in Fig. 6. Lower die 6 also has an upright forming wall 31 for producing the contour depicted 90 at 31^b in Fig. 6. The under face 32^b of the section shown in Fig. 6 is formed by that portion of the upper face of lower die 6 which is contiguous the perimeter of the upper edge of upright wall 31 of lower 95 die 6, while the lowest frusto-conical subdivision 33^b of the section illustrated in Fig. 6 is adapted to be produced by the correspondingly shaped lowest portion 33 of upper die 7. The next highest frusto-conical portion indicated at 34^b, Fig. 6, is adapted to be formed by the similar female conical frustum 34 superposed above shaping portion 33 of upper annular die 7. The more nearly cylindrical, but still 105 frusto-conical, portion 35^b of the section shown in Fig. 6, is adapted to be produced by the female conical frustum 35 of upper die 7, and the upper beveled edge 36^b of the ring section shown in Fig. 6, is created 110 by the downwardly and outwardly inclined face 36 on the under side of the upper die holder-guiding portion of pilot 10.

The operation of the machine is as follows:

Desiring to convert a ring, the cross section of which is similar to that shown in Fig. 5, *i.e.*, rectangular, to the peculiar cross section depicted in Fig. 6, the parts of the machine are brought into the position illustrated in Fig. 1 and the ring of rectangular section is placed upon lower die 6 so that its lower annular edge projects into said die until brought to rest by the formation of the ring-forming surfaces, when it will occupy 120 substantially the positions shown in dotted and dashed lines 30^c in Fig. 1. Through any suitable means, various types of which are well known in the art, the movable table is actuated by a pressure which is sufficient 125 to

to displace the molecules of the ring to be treated. During such movement, the upper surface of lower die 6 will first encounter the under surface of upper die 7 and the upper portion of ring 30^e will be advanced between the inner wall of upper die 7 and the outer wall of pilot 10, the lower end of the latter being curved inwardly to, relatively speaking, enter ring 30^e. Upper die holder 8, at this time, is supported on the heads 16 of suspension pins 15, and this support is resilient due to the expansion of the tension suspension springs 17. When the lower die 6 is brought into contact with the upper die 7, the upper die-holder changes its position on the guide bolts, so that the heads 28 of said bolts are removed some distance from the upper face of ears 14 of upper die-holder 8. The operation continuing with the upper and lower dies in contact, the pilot will be caused to pass through both dies, the upper die sliding along the guide formed therefor by the cylindrical bearing portions of pilot 10 and pilot holder 11, suspension springs 17 gradually closing as they are relieved from the weight of the upper die holder and the die which it carries. This action continues and the upper ends of compression springs 23 engage the under face of flange 21 of the pilot holder 11, gradually becoming compressed as the movable table 2 proceeds to its ultimate position. When this position is attained the under faces of ears 14 of the upper die holder have moved away from the upper faces of the heads 16 of the suspension pins 15, and the work, *i. e.*, ring 30^e is forced between the inner and outer faces of upper die 7 and pilot 10, respectively, until its upper edge 36^a is brought into contact with and conformed to the face 36 of pilot 10. When this is accomplished, the female frusto-conical portions 33, 34 and 35 of the upper die 7 have been caused to assume the positions shown in Fig. 4, and the faces 30 and 31 of the lower die also have been caused to assume their final positions. Said inclined faces 36 and 30 of the pilot and lower die, respectively, are now more closely juxtaposed than the edges 30^a and 36^a of the rectangular ring were before the operation began to take place, and, as a relatively heavy pressure has been exerted upon the metal of the work, that is to say, the ring, said metal has been displaced until it has become conformed to the various faces included in the lower die, the upper die and the pilot holder, and the desired cross section has been given to what was originally, the ring of rectangular cross section. This desired cross section, in the present instance, corresponds to that shown in Fig. 6.

It is to be noted that the pilot 10, not only serves as a backing and guide for the ring to be altered, but that it also ultimately passes through the central aperture in lower

die 6. Inspection of Fig. 4 clearly shows that it, therefore, serves as a guide for both the upper and lower dies 6 and 7, respectively. These are consequently maintained in accurate and proper relation to each other and said pilot. When the dies and pilot come to their final shaping positions, their faces in the aggregate correspond in shape and dimension to the sum of those the altered form of the ring is to possess.

The work having been performed, the movable table is caused to recede to its former or initial position and as it does so, compression springs 23 exert a downward thrust upon the upper die holder 8, which, in turn, causes the upper die 7 to strip the newly formed ring from the pilot 10, and said ring will remain seated in lower die 6 from which it may be removed and a new ring substituted for similar treatment.

Compression springs 23 gradually assume the positions shown in Fig. 1 as the upper die holder travels downwardly; the under faces of ears 14 of said upper die holder 8 again engage the heads 16 of suspension pins 15, placing the suspension pins under increasing tension, and all of the parts resume their initial positions without jar, the operation of the machine in both directions being entirely smooth.

With the use of the machine herein before described, rings or other shaped articles may be transformed from one shape to another, in a single operation, and with the advantage of great economy.

I claim:

1. In combination, a work-holding-and-propelling forming die, an opposed forming-die, a guide member extending into the latter and forming an internal space between the same and itself, and means for causing said first mentioned forming-die to force work into said space and to compress the work, said forming-dies and guide member being adapted to expand said work at predetermined locations.

2. In combination, a work-holding-and-propelling forming-die, an opposing movable forming-die, separate means for driving each die toward the other die and a pilot member extending into said opposing die and forming a space between the same and itself, said work-holding forming-die being adapted to force work into said space and move said opposing die so that said forming-dies and pilot member cooperate to compress said work and to give variant thickness to its cross section.

3. In combination, a forming-die, an opposing movable forming die, a pilot member provided with a contour substantially corresponding to the intended interior contour of a piece of work, both of said dies being annular internally and normally out of engagement with said pilot member, and means for

75

85

95

100

105

115

120

125

130

moving the first mentioned forming-die to cause it to force the work between said opposing forming-die and said pilot member and to make such relation between itself, 5 said opposing forming-die and pilot member that said work is compressed and given a variant cross section.

4. In combination, a forming-die adapted to be driven and an opposing forming-die under oppositely acting movement influences 10 when in its normal position, both of said dies having internal portions substantially corresponding to the intended contour of external portions of a piece of work, and a pilot member provided with an external contour substantially corresponding to the intended interior contour of the work, and means for actuating said driven forming-die to overcome one of said influences applied to the opposite die and to force the 15 work between said opposing forming-die and pilot member and to so adjust itself and said opposing forming-die to said pilot member that the work is compressed and given a variant cross section.

5. In combination in ring-shaping apparatus, a forming die adapted to be driven and an opposing movable die, means for resiliently positioning the latter, a pilot member with which said opposing die is adapted 20 to contact and to have relative movement with, and means for driving said driven die, the last mentioned die being adapted to become interlocked with said pilot member and co-operatively related to said opposing die and to actuate the latter so that a ring 25 of suitable thickness may be forced between said pilot member and opposing die and become compressed and given a variant thickness.

6. In combination in ring-shaping apparatus, a forming-die adapted to be driven, an opposing forming-die having an opening, a movable die-holder therefor inseparable in all of its positions, means for guiding 45 said die-holder, a pilot member of less diameter than the opening in said opposing die and means for so driving the driven die that a ring of suitable thickness may be forced between said pilot member and said opposing die, there being a resultant positioning of said forming-dies and pilot member whereby said ring is beveled on its lateral edges and given a variant thickness.

7. In combination in ring-shaping apparatus, a forming die adapted to be driven, an opposing forming-die, a movable die-holder therefor constantly embracing the same, means for guiding said die-holder, a pilot member extending into said opposing die and means for driving said driven die, movement of the latter being adapted to force a ring having inner and outer circumferential faces over said pilot member and 60 between the latter and said opposing die,

and also causing such positioning of said forming-dies and pilot member that said ring acquires beveled lateral edges and variant thicknesses between its circumferential faces.

8. In combination in ring-shaping apparatus, a forming die adapted to be driven, an opposing forming-die, a movable die holder therefor, a pilot member extending into said opposing die, movement of said driven die being adapted to force a ring having parallel inner and outer circumferential faces over said pilot member and between the same and said opposing die, and also causing such positioning of said forming-dies and pilot member that said ring acquires beveled lateral edges and variant thicknesses between said circumferential faces, and means for causing said opposing die to act as a stripper for said ring.

9. In combination in a ring-shaping apparatus, a forming-die, an opposing forming-die and a pilot member provided with a forming-die, said elements being provided with work-treating faces, and means for bringing said dies and pilot member into correlation to form a ring-receiving-and-shaping chamber, the space in said chamber corresponding in form to a ring provided with oppositely beveled opposing edges and outer 95 and inner circumferential faces and also having a plurality of successive portions, a number of said portions each having an unequal thickness between said circumferential faces greater in part than a next adjacent portion.

10. In combination in ring-shaping apparatus, a forming-die having an exposed face, an opposing forming-die and a guide provided with a forming-die, said elements 105 having portions adapted to fashion a ring having outer and inner circumferential faces, some of said portions having reversely inclined faces for oppositely beveling opposing edges of the ring, other portions having 110 opposingly spaced annular faces for treating said circumferential faces of the ring, said opposing annular faces not being in constant parallelism, and means for bringing said elements into such co-operative relation that a ring is compressed and given a variant cross section, the faces of said fashioning portions forming a dovetail outline that is imparted to the cross section of the ring, and a portion of said exposed face being adapted to form a shoulder in the ring.

11. In combination in apparatus of the class described, a plurality of forming-dies and a guide all normally separated from each other and means for moving the same 125 together so as to form faces corresponding to the sum of the component altered faces of a transformed piece of work.

12. In combination in apparatus of the class described, a plurality of forming-dies 130

and a guide adapted to receive work and maintain said dies in a predetermined relation, said dies and guide being all normally separated and adapted to be moved together 5 to form the component faces of a transformed piece of work.

13. In combination in apparatus of the class described, die holders, means permitting limited movement therebetween, a resilient support for one of said die-holders, a pilot adapted to guide the latter and to receive annular work, and dies in said die-holders, said dies and pilot being adapted to compress annular work having parallel inner and outer circumferential faces, to form beveled lateral edges on said work and produce variant thicknesses between said circumferential faces.

14. In combination in apparatus of the class described, die-holders, means permitting limited movement therebetween, a resilient support for one of said die-holders, dies in said die-holders and a pilot adapted to guide the dies and said resiliently supported die-holder and to receive work, and also to coöperate with said dies to compress annular work having inner and outer circumferential faces, to form beveled lateral edges on said work and produce variant thicknesses between said circumferential faces.

15. In apparatus of the class described, a plurality of work-shaping members having coöperative form-determining faces, said members being all normally separated from each other and being adapted to be brought together to change a ring having a substantially rectangular cross section to a ring having a substantially uniform bore, beveled lateral edges and a series of superposed geometrical frustums, the cross section of the altered ring having a dovetail formation.

16. In apparatus of the class described, a plurality of work-shaping members having coöperating form-determining faces, said members being normally separated, and means for bringing said members into contiguity to compress a ring having a substantially rectangular cross section and by reason of the fashioning of the form-determining faces to convert it into a ring having a substantially uniform bore, beveled lateral edges, a series of geometrical frustums arranged in immediate and uninterrupted succession each frustum being of increased base diameter and an annular portion of less diameter than the frustum of greatest diameter adjacent the latter, said ring having a dovetail cross section.

17. In combination in ring-shaping apparatus, a forming-die adapted to be driven, an opposing forming-die, a movable die-holder therefor, a pilot member extending into said opposing die, movement of said driven die being adapted to force a ring

having inner and outer circumferential faces over said pilot member and between the same and said opposing die, and also causing such positioning of said forming-die and pilot member that said ring acquires 70 beveled lateral edges and variant thicknesses between said circumferential faces and means for causing said opposing die to act as a stripper for said ring.

18. In combination in apparatus of the class described, die holders, means permitting limited movement therebetween, a resilient support for one of said die-holders, a pilot adapted to guide the latter and to receive annular work, and dies in said die-holders, said dies and pilot being adapted to compress annular work having inner and outer circumferential faces, to form beveled lateral edges on said work and produce variant thicknesses between said circumferential faces.

19. In combination in apparatus of the class described, a pilot-holder, a removable pilot secured thereto, a die-holder adapted to travel longitudinally of said pilot-holder 90 and pilot, a second die-holder, dies in said die-holders, resilient suspension means for supporting the first mentioned die-holder, and means for moving said die-holders to predeterminedly position said dies with respect to the pilot.

20. In combination in apparatus of the class described, a pilot-holder, a pilot interlocked therewith, a die-holder adapted to be penetrated by and to travel over said pilot-holder and pilot, a second die-holder, dies in said die-holders, means for resiliently suspending the first mentioned die-holder, said means being supported from said pilot-holder, and means for moving said die-holders to predeterminedly position said dies with respect to said pilot.

21. In combination in apparatus of the class described, a pilot device, a die-holder movable thereon, another die-holder, dies in the die-holders, a resilient support for the first mentioned die-holder, means for moving the second mentioned die-holder to cause said dies to engage and become predeterminedly positioned with respect to said pilot device and to move said first-mentioned die-holder, and means for pressing the first mentioned die-holder during such movement toward the second mentioned die-holder.

22. In combination in apparatus of the class described, a pilot device, a die-holder, an opposing die-holder, dies in the die-holders, a resilient support for the first mentioned die-holder, means for moving said opposing die-holder to cause said dies to become predeterminedly positioned with respect to the pilot device and to move the first mentioned die-holder, and means normally limiting the separation of said die-holders becoming non-limiting when said first men-

tioned die-holder moves in response to the action of the means for moving said opposing die-holder.

23. In combination in apparatus of the 5 class described, a die-holder, an opposing die-holder, dies in the die-holders, a resilient suspension support for the first mentioned die-holder, means carried by one die-holder normally limiting the separation of the 10 other die-holder therefrom, and means for moving said opposing die-holder and causing the first mentioned die-holder to move without restraint from said separation-limiting means and out of supported relation 15 with said resilient support.

24. In combination in apparatus of the 15 class described, a pair of die-holders, dies therein, a resilient means for supporting one of said die-holders and means for moving 20 the other die-holder so that said resilient means is relieved of the support of the die-holder it sustained, the last mentioned die-holder having its support transferred in effect to the other die-holder.

25. In combination in apparatus of the 25 class described, a die-holder, an opposing die-holder, dies in the die-holders, a resilient suspension support for the first mentioned die-holder, adjustable means carried by one 30 die-holder normally limiting the separation of the other die-holder therefrom to a desired degree, and means for moving said opposing die-holder and causing the first mentioned die-holder to move without restraint 35 from said separation-limiting means and out of supported relation with said resilient support.

26. In combination in apparatus of the 40 class described, a die-holder, an opposing die-holder, a pilot, dies in the die-holders, a resilient suspension support for the first mentioned die-holder, means normally limiting the separation of said die-holders, means for moving said opposing die-holder 45 to cause the first mentioned die-holder to act independently of said resilient suspension support and separation-limiting means and to predeterminedly position the dies with respect to said pilot, and means for pressing 50 the first mentioned die-holder toward said opposing die-holder, which means are effective subsequently to the action of the first mentioned die-holder that is independent of said resilient suspension support and 55 separation-limiting means.

27. In combination in a ring-forming machine, a pilot-holder and pilot, a resiliently supported die-holder and die normally telescoped upon said pilot, a second die-holder 60 and die, means adapted to cause the pilot to extend through both of said dies and means connecting both die-holders adapted to limit movement of said first mentioned die-holder relatively to said pilot.

28. In combination in a ring-forming ma-

chine, a pilot-holder, a pilot, a resiliently supported die-holder, a die connected with said die-holder, a second die-holder and die movable relatively to said first mentioned die, movable means adapted to cause separation of the pilot and one die from the second die holder and its die and means connecting both die-holders adapted to limit movement of one of said dies. 70

29. In combination in a ring-forming ma- 75 chine, a pilot-holder, a pilot, a resiliently supported die-holder and die normally telescoped upon said pilot, a second die-holder and die adapted to telescope with said pilot, means adapted to cause relative movement 80 of said dies and pilot-holder and means adapted to limit relative movement of said dies when the pilot is withdrawn from said dies.

30. In combination in a ring-forming ma- 85 chine, a pilot member, a resiliently supported die transversely spaced therefrom, both being provided with work determining faces, a second die, means adapted to prevent excessive separation of said dies, and means 90 for causing relative movement between said pilot and both of said dies to shape work between both dies and the pilot. 95

31. In combination in a ring-forming ma- 100 chine, a pilot member, a resiliently supported die-holder and die spaced from said pilot and telescoped thereupon, a second die holder and die, both dies and the pilot having opposing work-shaping faces, and means for causing relative movement of said pilot and dies to shape work between the dies and between them and the pilot. 105

32. In combination in a ring-forming ma- 110 chine, a pilot member, a resiliently supported die-holder and die spaced from said pilot and telescoped thereupon, a second die holder and die, both dies and the pilot having opposing work-shaping faces, means adapted to prevent excessive separation of said dies, and means for causing relative movement of said pilot and dies to shape work between the dies and between them and the pilot. 115

33. In combination in a ring-forming ma- 120 chine, a pilot-holder, a pilot member, a resiliently supported die transversely spaced therefrom both being provided with work-determining faces, yieldingly mounted suspension means supporting said die from said pilot-holder, a second die, means adapted to prevent excessive separation of said dies and means for causing relative movement between said pilot and both of said dies to shape work between both dies and the pilot. 125

34. In combination in a ring-forming ma- 130 chine, a pilot-holder, a pilot member, a resiliently supported die-holder and die spaced from said pilot and telescoped thereupon, a second die-holder and die, both dies and the pilot having opposing work-shaping faces,

guide means for said die-holders, resilient supporting means for one die-holder connected with said pilot-holder, and means for causing relative movement of said pilot and 5 dies to shape work between the dies and between them and the pilot.

35. In combination in a ring-forming machine, a pilot member, a resiliently supported die-holder and die spaced from said pilot 10 and telescoped thereupon, a second die-holder and die, both dies and the pilot having opposing work-shaping faces, means adapted to prevent excessive separation of said dies, means for causing relative movement 15 of said pilot and dies to shape work between the dies and between them and the pilot, and rigid guiding means on which one of said die-holders is adapted to slide.

36. In combination in a ring-forming machine, a pilot member, a resiliently supported die transversely spaced therefrom, both being provided with work-determining faces; yielding means normally supporting said die, means adapted to limit travel of 25 said die, a second die, and means for causing relative movement between said pilot and both of said dies to shape work between both dies and the pilot.

37. In combination in a ring-forming machine, a pilot member, a resiliently supported die-holder and die spaced from said pilot and telescoped thereupon, a second die-holder and die, both dies and the pilot having opposing work-shaping faces, means for 35 causing relative movement of said pilot and dies to shape work between the dies and between them and the pilot, and positively acting means connecting both die-holders adapted to permit separation thereof while 40 limiting the degree of such separation.

38. In combination in a ring-forming machine, a pilot member, a resiliently supported die-holder and die spaced from said pilot and telescoped thereupon, a second die-holder and die, both dies and the pilot having opposing work-shaping faces, means permitting separation of said dies but adapted to prevent excessive separation thereof, and means for causing relative movement of said 50 pilot and dies to shape work between the dies and between them and the pilot.

39. In combination in a device of the class described, opposing die holders, perforated co-acting dies carried thereby, a pilot passable through said opposing dies adapted to be spaced from portions of each, means normally separating said die holders, devices connecting said die holders limiting their separation, and means for actuating said 60 die-holder-connecting devices and relatively

moving said die holders together and said pilot through said dies so that the pilot will be spaced in part from each die.

40. In combination in a device of the class described, spaced opposing die holders 65 yieldingly connected, co-acting dies carried thereby, a work-backing pilot passable through said dies normally out of engagement with one of said dies, means for causing said die holders to bring said dies together and for projecting said pilot through said dies, and auxiliary guiding means for alining said die holders effective at times when said pilot is not projected through the dies of said opposing die holders. 70 75

41. In combination in a device of the class described, opposing dies, die holders therefor, means normally separating said die holders, means connected to both die holders restraining the same from further separation 80 when said last mentioned means is in a given relation to said die holders, a pilot for said dies and means for bringing said dies and pilot into work-shaping relation.

42. In combination in a device of the class described, co-acting dies, opposing die holders therefor, a pilot, actuating means for moving the die holders toward each other and said pilot through said dies into work-shaping relation therewith, said means having a stroke, means normally separating said die holders, separation-limiting devices so connecting said die holders that their influence is nullified during the stroke of said actuating means and by acting through one 90 of said die holders is adapted to cause the die therein to strip work from said pilot upon a return stroke of said actuating means. 95

43. In combination in a device of the class 100 described, opposing movable die holders, perforated co-acting dies carried by said holders, a pilot normally out of contact with said dies and passable through the same to form space between itself and said dies, 105 means maintaining said die holders in spaced but yielding relation, guides extending into one of said die holders and effective to cause the alinement of said dies when said 110 pilot is incapable of doing so, and means for moving said die holders and pilot to bring the latter and said dies into work-forming relation.

In witness whereof I have hereunto set 115 my hand in the presence of two witnesses.

FREDERICK A. STEVENSON.
